SLICING MACHINE WITH HAND-OPERATED MATERIAL FEEDER

Patrick J. Lucey, Chicago, Ill.

Application December 22, 1930, Serial No. 503,899

5 Claims. (Cl. 146—102)

This invention relates to a slicing machine with hand-operated material feeder.

One of the main objects of this invention is to provide an inexpensive slicing machine wherein the material is fed by hand and the hand is protected from injury while feeding the material to the slicing knife.

Another object of this invention is to provide an inexpensive slicing machine including means wherewith to engage the material and feed it manually to the slicing knife, in such a manner that even the small end-piece will be firmly held during slicing and the entire mass of material will be properly sliced.

Still another object is to provide, in a slicing machine of the hand-fed type, means whereby to hold the material firmly and feed it manually, so that the entire mass of material can be completely and properly sliced, without endangering the hand thereby.

A further object of this invention is to provide means whereby to feed the material manually to the knife and which means will function, during the inoperative period of the machine, as guard means for the cutting portion of the knife, which is exposed during the slicing operation and has heretofore been left exposed also during the period of rest, in this hand-fed type of machine.

A still further object is to provide a machine of this type with a pusher or member for feeding the material manually to the knife, and which is arranged so that the pusher will adjust itself automatically for limiting its movement to the knife edge, in harmony with the adjustment of the gage plate for the particular thickness of slice desired.

These and other objects and advantages are attained with this invention, as will become apparent from the following description, taken in connection with the accompanying drawings, in which,—

Fig. 1 is an end elevational view of a slicing machine embodying my present invention in its preferred form of construction.

Fig. 2 is a top plan view, partly in section, taken on line 2—2 of Fig. 3, looking in a downwardly slanting direction.

Fig. 3 is a side view, partly in section, taken on line 3—3 of Fig. 1, looking in an upwardly slanting direction.

Fig. 4 is a sectional view, taken substantially on line 4—4 of Fig. 3, thereby cutting the knife edge at about mid-elevation, and additionally showing the adjustable stop elements near the top of the knife, as shown in Fig. 2.

Fig. 5 is a side elevational view of my novel ma-

terial feeding member or material pusher, which protects the hand in feeding the material to the slicing knife.

In the drawings my invention is illustrated in its preferred form of construction, which comprises a supporting base 10 wherefrom a bracket 11 slants upwardly and carries a cap or housing portion 12 at its upper end containing the means for rotatably mounting the circular slicing knife 13. A motor 14 is mounted on bracket means 15 provided on the base, for driving said knife with suitable driving connections, as by the use of suitable pulley and belt means 16, as indicated in the drawings.

A material rest or table 17, substantially in the form of a plate, is mounted on the base, to extend at an inclination to the horizontal, preferably at forty-five degrees. Its main upper part 17' provides the supporting face or portion whereon the material rests and is moved during the slicing operation; and its lower part 17'' provides an apron which extends from said upper supporting part at a slant downwardly and rearwardly, at one side of the knife and from about mid-elevation thereof, said apron having its lower end secured to the base, with screws or the like. The upper part 20 of the material rest or table is mounted on leg means 18 arising from the base.

A gage plate 20 is mounted on the material rest or table 17, preferably to extend substantially at right angles thereto, the upper part or face 17' of said table, in conjunction with the adjacent face of the gage plate, providing the feedway or slide-way on which the material is slid or moved during the slicing operation. Said feedway is formed trough-like, being preferably V-shaped in cross-section, substantially as shown in the drawings.

Means is provided for adjustably mounting the gage plate on the material rest, comprising a casing or foot portion 21 extending rearwardly from the lower end of said plate and being adjustably held on the apron 17'' of said rest, preferably by the use of screws 22 which are movable in slots 23 provided in apron 17'' and are threaded into lugs 24 provided in said casing. A cup 25 surrounds the outer part of each screw, and bears frictionally against the outer or lower side of said apron; while a coil spring 26 is placed in each cup, being confined between the head of the screw and the bottom of the cup; so that the lugs 24 are firmly drawn and frictionally held against the inner side, and the cups against the outer side of said apron. The gage plate is thereby held firmly in its adjusted position, and so as to permit adjustment thereof relative to the material rest and the knife.

Setting means is provided for adjusting or setting the gage plate on the material rest, relative to the knife, for providing the particular thickness of slice desired, and this means preferably 5 comprises a setting knob or index knob 27 having numbers or indicia 28 thereon, to co-operate with a finger 29 on the machine, for indicating the particular adjustment of the gage plate according to the particular thickness of slice desired. 10 The knob is attached to suitable actuating means, being preferably secured to the outer end of a shaft 30 which is journaled in casing 21 and carries on its inner end a pinion 31 in mesh with a rackbar 32 which is secured on the upper side of 15 said apron.

In adjusting or setting the gage plate, by turning the knob the pinion 31 travels over the rackbar 32, thereby sliding the casing over the apron of the material rest and adjusting it thereon, relative to the knife edge, to the desired position. 20 The springs 26 permit sufficient separation of the lugs 24 and the cups 25, to enable said cups and lugs to slide along the apron, when the knob is turned; and the springs are under sufficient compression or strain to normally hold the cups and lugs firmly set on the apron, and retain the gage plate properly in the set position. 25

This slicing machine I provide with means whereby to engage the material and feed it by hand along the feedway to the slicing knife. Said 30 means preferably comprises a feeding member or pusher 35, as best shown in Fig. 5 of the drawings, which is provided with a handle 36 at the outward and rearward part thereof, to be grasped by the hand, and which is so arranged that the hand is protected from injury by the knife while feeding the material thereto. Said feeding member has its front portion or face portion 37 arranged to engage and hold a mass of material 35 securely while sliding it along the feedway to the knife edge, and it preferably has said face portion curved in harmony with the knife edge and has the upper part 37' of said portion projecting forwardly so that the material is urged downwardly 40 on the feedway. The face portion is also arranged to urge the material, and particularly the final portion or an end-piece, inwardly toward the knife and the gage plate, so as to securely hold and properly feed the entire mass of material; and for that reason said front face portion 45 is provided with a beveled side portion 38 at its inward side, adjacent the gage plate, which has its inward front edge cut-away to provide a beveled edge or face 38', so that even a small end-piece will be urged and pressed toward the gage plate and securely held thereby while being fed to the knife. Said beveled portion 38' thus bears back of the end-piece or the final portion of material for pushing the latter against the knife edge, 50 and is movable with said end-piece in the plane extended through said edge.

The feeding member or pusher 35 is mounted to be moved manually along the feedway for feeding the material thereon to the knife; and 55 the means for mounting it preferably comprise guide means connected with the gage plate 20. Said guide means includes, in this illustrated form, a pair of guide rods 40 which are secured on lugs 41 extending from the rear of the gage 60 plate near the knife, and on lugs 42 extending from the rear of arms 43 which project from the end of the gage plate away from the knife. A web or plate-like member 44 has a pair of parallel sleeves 45 provided at its opposite ends, which 65 are slidably mounted on said guide rods 40, as by

the use of bearing means 46. A curved arm or yoke 47, which extends over the top edge of the gage plate, connects the feeding member positioned at the front of said gage plate with the web member 44 and its sleeves 45 positioned at the rear of said plate, so that said feeding member or pusher is slidably mounted for slidable movement along the feedway. 5

Stop means is provided for limiting the travel of the feeding member, and stopping it just before its beveled edge 38' engages the edge of the knife. This means includes a finger or stop element 48 provided at the side of yoke 47 and having a beveled front edge or face 48', said edge 48' and the beveled edge or face 38' being so beveled that a pair of horizontal lines extending through said two edges will be parallel to each other, as is best apparent from Fig. 4. A companion stop element or finger 49 is mounted on the machine, being preferably mounted on an arm 50 extending 20 horizontally from a bracket 51 which arises from cap 12 of the machine. Said element 49 has a beveled edge or face 49' which is beveled in harmony with its companion beveled edge 48' on finger 48. 25

With this construction the stop elements 48 and 49 and the side portion 38 are so arranged, and they have their faces 48', 49', and 38' so beveled, that when the gage plate is adjusted relative to the knife, by turning knob 27 and actuating the 30 adjusting means according to the thickness of slice desired, these companion beveled faces 48' and 49' will operate to automatically adjust the feeding member 35 so that its beveled face 38' will be stopped immediately adjacent the edge of 35 the knife; whether said feeding member is located at the outer side of its adjustment, substantially as shown in Fig. 2, or is located near the inner side, substantially as shown in Fig. 4. With this arrangement the feeding member or 40 pusher is thus automatically adjusted in its movement to the knife edge, along with the various adjustments of the gage plate and in exact accord therewith. 45

I also make these stop elements adjustable, to 45 provide for different diameters of knives, and for the varying diameter of a knife, as for instance, when the diameter of the knife is decreased due to the continuous sharpening of the knife edge; whereby the feeding member or pusher can be re-adjusted or reset, so that its beveled edge 38' will again stop immediately adjacent the knife edge. 50 For readily making this adjustment I provide slots 53 in the stationary stop element 49, and screws 54 which extend therethrough and are threaded into arm 50 for clamping said element onto said arm; so that said normally stationary, but adjustable element 49 can be readily and accurately adjusted on the fixed arm 50 on the machine. 55 60

Guard means 56 is provided for guarding the main or major part of the knife edge, as is customary in these slicing machines, that part outside of the portion which is active and necessarily uncovered in cutting the material as it is being fed thereto, this cutting portion being indicated by numeral 57 in Figs. 3 and 4. Said guard means is secured and supported on the machine with any suitable means, which may include a screw 58 and an arm 59 extending from said guard means 70 and being secured by said screw onto the arm 50 of bracket 51.

In this invention my feeding member 35 is arranged to be utilized as auxiliary guard means, for guarding said cutting portion 57 of the knife 75

edge while the machine is inactive or at rest, and which portion is normally left unguarded. For this reason feeding member 35 has its face portion 37 curved in conformity with the knife edge and made of an exact size to extend from the upper part of said guard means 56 down to the lower part 56' thereof; so as to extend along and to guard the entire normally exposed cutting portion 57 of the knife edge.

5 It is consequently apparent, that, by the adjusting or setting of the gage plate on the material rest, in accordance to the thickness of slice desired, the side portion 38 of the feeding member 35 has its part near the gage plate positioned substantially in the plane of the knife edge, and back of the slice of material which is about to be sliced; thus providing a firm support therefor to assure proper slicing of the entire mass of material, and complete slicing of even a small end-piece; and furthermore, it becomes evident that this feeding member 35 will function as a guard for the cutting portion 57 of the knife edge, by merely pushing it to the limit of its travel toward said edge, whereupon this member along with said guard means 56 will provide a complete guard for the knife.

10 I claim as my invention:

1. A slicing machine comprising a rotary knife, a material rest and a gage plate adjustably mounted thereon and which therewith provides a feedway for the material, guide rod means on the outer side of said gage plate and positioned rearwardly of the plane through the knife edge, and a material feeding member slidably mounted on said guide rod means to be moved manually for sliding the material along said feedway.

2. A slicing machine comprising a horizontal base having a rotary knife mounted inclined thereon, a trough-shaped feedway including a material rest and a gage plate which is adjustable relative to said rest and wherealong the material is fed to the knife, a hand-engaged material feeding member and coengaging means on said member and on the gage plate rearwardly of the plane through the knife edge, whereby said member is movably mounted on the gage plate for feeding the material to the knife.

3. In a slicing machine provided with a rotary knife and a feedway on which the material is fed 15 against the knife edge, a feeding member and co-

operating means thereon and on the machine whereby said member is slidably mounted to be moved manually along said feedway, a beveled part on said member to bear back of an end-piece and to be moved therewith in the plane of the knife edge, and stopping elements on said member and on the machine for stopping the member when the beveled part is close to the knife edge, said elements having their coengaging portions beveled in conformity with the beveled part on said member, whereby said beveled part is properly stopped directly adjacent the knife edge.

4. In a slicing machine, a rotary knife, a material rest and a gage plate which is adjustable relative to the rest and which therewith provides a trough-shaped feedway for the material, a manually operated pusher member, for feeding the material along the feedway, guide means on the rear face of the gage plate rearwardly of the plane through the knife edge, means extending from said member and engaging said guide means to guide said member, and coengaging stop elements on said member and on the machine for stopping said member when closely adjacent the knife edge, said elements having their coengaging parts beveled so that the member automatically adjusts itself to stop short of the knife edge in harmony with the adjustment of the gage plate on the material rest.

5. In a slicing machine, a rotary knife, a material rest and a gage plate which is adjustable relative to the rest and which therewith provides a feedway for the material, a manually operated member for pushing the material along the feedway to the knife edge, guide means on the outer side of the gage plate, means on said member to slidably engage said guide means, said member having a part thereon which is beveled to hold and to push an end piece of material toward the gage plate and against the knife edge, said beveled part being movable into the plane of the knife edge and including means to provide a guard for the cutting portion of the knife edge, coengaging beveled stop elements on said member and on the machine for stopping the member when the beveled part is close to the knife edge, and means for adjusting one of said stop elements whereby to accommodate any variation in the size of the knife due to continued sharpening.

PATRICK J. LUCEY. 50
